UNITED STATES PATENT OFFICE.

SAMUEL D. REID AND ELLA M. REID, OF BURLINGTON, KANSAS.

COMBINED LAP-ROBE AND STORM-APRON.

SPECIFICATION forming part of Letters Patent No. 746,743, dated December 15, 1903.

Application filed July 20, 1903. Serial No. 166,338. (No model.)

To all whom it may concern:

Be it known that we, SAMUEL D. REID and ELLA M. REID, citizens of the United States, residing at Burlington, in the county of Coffey and State of Kansas, have invented a new and useful Combined Lap-Robe and Storm-Apron, of which the following is a specification.

This invention relates to a combined lap-robe and storm-curtain for vehicles; and the object of the device is to provide means whereby the identity thereof as a lap-robe will not be apparent when used as a storm-curtain, and vice versa.

Another object is to effectually conceal the attaching edges of the apron within a pocket when not in use.

Further objects and advantages of this invention, as well as the novel details of construction, will be referred to hereinafter, reference being had to the accompanying drawings, in which—

Figure 1 is a perspective view of the invention, showing the position of the parts as a storm-curtain. Fig. 2 is a perspective view of the device as a lap-robe. Fig. 3 is a sectional view on the line *a a* of Fig. 1. Fig. 4 is a sectional view on the line *b b* of Fig. 1. Fig. 5 is a sectional view on the line *c c* of Fig. 1. Fig. 6 is a sectional view on the line *d d* of Fig. 2. Fig. 7 is a sectional view on the line *e e* of Fig. 2, and Fig. 8 is a sectional view on the line *f f* of Fig. 2.

The device is illustrated as comprising two sheets 1 and 2, of fabric, either of which is lined with a sheet 3 of material impervious to moisture, the edges of the several sheets being connected by a felled seam 4 on three sides, forming a multi-ply structure in the form of a pocket, within which the attaching edges of the storm-curtain are normally contained, and which is capable of being inverted or turned inside out to provide a storm-apron or a lap-robe, as desired.

5 and 6 designate the side flanges of the curtain, and 7 and 8, respectively, designate the top and bottom flanges, all of which constitute the attaching edges of the device when used as a storm-curtain. The connect- ed edge of each flange except the top one is contained within the felled seam 4, so that both sheets 1 and 2, the lining 3, and the

flanges 5, 6, and 8 can all be secured together by a single operation or by providing a single seam. The edge of the top flange is attached to the device slightly below the open edge of the pocket, so as to prevent any liability of the water passing through the seam and into the pocket and so that it will be shed upon the curtain or apron.

At suitable points on the impervious sheet are fastening members 9, adapted to coact with complementary members 10 on the flanges or flaps in order that the flaps can be folded down upon the sheet and held when the storm-curtain is not used as such.

Opposite to the fastening members 10 are similar members 11, which coincide with suitable devices upon the vehicle to be engaged when the flaps are free and exteriorly accessible. Exterior and interior fastening devices 12 and 13 are also provided at the open end of the pocket, so that the opening can be closed, although, if desired, the feet of the occupant of the vehicle can be placed in the pocket above described. In order to protect the lower edge of the device, a binding 14 is provided, which will assist the water to pass off from the impervious sheet 3 as well as protect the fabric.

In practice the flaps 5, 6, and 8 will be made a part of the sheet 3, while the flap 7 will be a separate part, thus materially reducing the cost of manufacture.

Having thus described our invention, what we claim is—

1. A combined lap-robe and storm-apron comprising a pocket-like structure having flaps normally disposed on the inside of said pocket in inaccessible position, said flaps being accessible when the pocket is in its reversed position.

2. A convertible lap-robe and storm-apron, comprising a multi-ply pocket-like structure capable of being inverted to bring the desired surface outside and having securing edges for fastening it to a vehicle, said edges being accessible in one position of the structure and inaccessible in its reversed position.

3. A storm-apron, comprising a pocket with a sheet of impervious material normally within the pocket and overlapping securing-flaps normally carried within the pocket.

4. A storm-apron, comprising a pair of fab-

ric sheets, a lining-sheet of impervious material, and securing-flaps connected to edges of the sheets by a single seam.

5. A device of the class described, comprising a pocket with securing-flaps having oppositely-disposed fastening members and complementary fastening members in the pocket.

6. A device of the class described comprising a plurality of sheets secured together along their edges on three sides thereof to form a pocket-like structure and having securing-flaps attached to said edges within said pocket.

7. A device of the class described comprising a plurality of sheets secured together along their edges on three sides thereof and detachably connected at the other side to form a pocket-like structure, and having secur-

ing-flaps attached to said edges within said pocket.

8. A convertible storm-apron and lap-robe comprising two sheets of fabric with a sheet of waterproof material disposed between them and secured together along a plurality of the edges thereof forming a pocket-like structure which in one position forms a lap-robe and in the other a storm-apron.

In testimony that we claim the foregoing as our own we have hereto affixed our signatures in the presence of two witnesses.

SAMUEL D. REID.
